DESIGN FOR AN X-RAY CONTROL STAND

Gerard Kloos, Mount Vernon, N. Y., assignor to
Philips Metalix Corporation, New York, N. Y.

Application November 1, 1939, Serial No. 87,982

Term of patent 7 years

To all whom it may concern:

Be it known that I, Gerard Kloos, a subject of the queen of the Netherlands and a resident of Mount Vernon, New York, have invented a new, original, and ornamental Design for an X-ray Control Stand, of which the following is a specification, references being had to the accompanying drawing, forming part thereof.

The figure is a perspective view of an X-ray control stand showing my new design.

The rear side of the stand is plain and the left hand side is substantially the same in appearance as the side shown.

I claim:

The ornamental design for an X-ray control stand, as shown and described.

GERARD KLOOS.
